UNITED STATES PATENT OFFICE.

BYRON H. WILLIAMS, OF SPOKANE, WASHINGTON.

HARNESS-OILING APPARATUS.

1,131,763.

Specification of Letters Patent. Patented Mar. 16, 1915.

Application filed January 20, 1914. Serial No. 813,172.

To all whom it may concern:

Be it known that I, BYRON H. WILLIAMS, a citizen of the United States, residing at Spokane, in the county of Spokane and 5 State of Washington, have invented certain new and useful Improvements in Harness-Oiling Apparatus, of which the following is a specification.

This invention relates to apparatus for 10 oiling harness, and its object is to provide an apparatus of this kind which is simple in construction, and easy to operate, and by means of which the harness can be quickly and thoroughly oiled with a minimum quantity 15 of oil, and without any waste of oil. This object is attained by means of a novel combination and arrangement of parts to be hereinafter described and claimed.

In order that the invention may be better 20 understood, reference is had to the accompanying drawing, in which—

Figure 1 is an elevation of the apparatus; Fig. 2 is a vertical section thereof on the line 2—2 of Fig. 1, and Fig. 3 is a horizontal section on the line 3—3 of Fig. 2.

Referring specifically to the drawing, 5 denotes a barrel or other suitable receptacle having trunnions 6 on opposite sides, whereby it is endwise rotatable on a suitable 10 stand, the latter having bearing standards 7 in which the trunnions are supported. The trunnions are fastened to the outside of the barrel, midway between its ends. In order 15 that access may be had to the interior of the barrel, one end thereof is provided with a removable lid or head 8, suitable means being provided for securely fastening the same in place when the apparatus is to be operated. As these fastening means form no 20 part of the present invention, they need not be described.

On the bottom of the barrel, on the inside 25 thereof, are mounted cross-strips 9 extending parallel to the axis of the trunnions 6. These strips are carried by a band 10 across which latter they extend, and to which they are fastened in any suitable manner. The 30 diameter of the band is such that it fits snugly in the barrel against the inner surface 35 thereof, at the bottom, to bring the strips against the barrel bottom. The cross-strips are triangular in section, the base being next to the barrel bottom, and the apex pointing toward the center of the bar-

rel. In the base of the strips are ducts 11 55 which are for a purpose to be presently made clear.

The harness to be oiled is placed in wire baskets 12, and the latter are placed in superposed position in the barrel 5, the lower 60 basket seating on top of the band 10, and the top basket fitting against the bottom of the lid 8, whereby the baskets are prevented from slipping back and forth in the barrel, and they are thus securely held in 65 place. The diameter of the baskets is such that they fit snugly in the barrel.

In operation, a suitable quantity of oil is placed in the barrel 5, and after the harness is placed in the baskets 12, and the 70 latter are positioned in the barrel as hereinbefore described and clearly shown in Fig. 2 of the drawing, the lid 8 is put on and fastened in place. The barrel is now revolved in opposite directions alternately, 75 or rocked, by means of a hand crank 13 connected to one of the trunnions 6, whereupon the oil in the barrel is splashed over the harness in the baskets, and the harness is quickly oiled. The oil will be spread by the 80 cross-strips 9 uniformly all over the harness, said strips preventing the oil from following the sides of the barrel, but causing the same to be thrown toward the center to cover the harness with oil. The baskets 85 space the harness from the strips 9. After the barrel 5 has been rocked a sufficient length of time to properly oil the harness, it is stopped and the oil is allowed to drain off and run back to the bottom of the barrel, 90 where it is permitted to seek its level, in view of the ducts 11. The baskets 12 may now be removed from the barrel upon taking off the lid 8.

The apparatus can be easily operated, and 95 it is economical in operation as there is no waste of oil. Any dirt which might gather in the bottom of the barrel can be readily removed, as the baskets, as well as the band carrying the spreader strips are removable. 100 The apparatus can also be used for blackening and washing harness.

The preferred embodiment of the invention has been shown, but it is to be understood that many changes in the structure 105 may be made without a departure from the spirit and scope of the invention as claimed hereinafter.

I claim:

1. The combination of a revoluble receptacle, transverse spreader strips in the receptacle projecting from one end thereof toward the center, and a perforated container in the receptacle above the spreader strips for spacing the contents of the receptacle from said strips.
2. The combination of a revoluble receptacle, transverse spreader strips in the receptacle projecting from one end thereof toward the center, and having transverse ducts, and a perforated container in the receptacle above the spreader strips for spac-

ing the contents of the receptacle from said 15 strips.

3. The combination of a revoluble receptacle having a removable closure at one end, a band in the receptacle seating against the other end thereof, and superposed containers in the receptacle removably held between the band and the closure.

In testimony whereof I affix my signature in presence of two witnesses.

BYRON H. WILLIAMS.

Witnesses:

O. J. SHOEMAKER,
ARTHUR L. DAVIS.
